CLAIM

The ornamental design for a protective ear covering for animals as shown and described.

DESCRIPTION

FIG. 1 is a perspective view of a protective ear covering for animals showing our new design;

FIG. 2 is a left side view thereof;

FIG. 3 is a front view thereof;

FIG. 4 is a right side view thereof;

FIG. 5 is a top view thereof;

FIG. 6 is a bottom view thereof;

FIG. 7 is a front cross-sectional view, taken in the direction of line 7-7 of FIG. 5;

FIG. 8 is a front view of the protective ear covering for animals of FIG. 1, shown in a first configuration in a condition of use; and,

FIG. 9 is a front view of the protective ear covering for animals of FIG. 1, shown in a second configuration in a condition of use.

Broken lines in FIGS. 8 and 9 depict environment and form no part of the claimed design.

1 Claim, 8 Drawing Sheets
